UNITED STATES PATENT OFFICE

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed August 11, 1919, Serial No. 316,649. Renewed January 23, 1924.

To all whom it may concern:

Be it known that I, MANSFIELD C. CRAWLEY, a citizen of the United States, and a resident of Groton, in the county of Tompkins, and State of New York, have invented certain new and useful Improvements in Typewriting Machines, of which the following is a specification.

The object of this invention is to provide a case-shift for motor-driven machines, the specific construction herein illustrated being especially adapted for use in that type of machine illustrated in my Patent 1,156,061, dated October 12, 1915, in which type of machine a continuously-running rotary motor is employed for operating the printing instrumentalities, the work of the operator being reduced simply to selecting the keys and lightly depressing them, the motor serving to supply all the power necessary for operating the type-bars. The general object of the present invention is to provide this type of machine with a case-shifting mechanism which will utilize the power of the motor to raise the case-shift support (i. e., platen-frame or the type-bar segment, as the case may be), the particular construction illustrated herein being especially adapted for that type of machine in which the platen is shifted up and down to obtain the case positions, as more fully hereinafter set forth.

In Patent No. 1,455,109, issued to me May 15, 1923, and in my co-pending application Serial No. 188,771, filed August 29, 1917, renewed April 16, 1923; now Patent 1,285,766, dated Mar. 4, 1924, two case-shift mechanisms are shown, each of which is adapted for use in a machine of the type set forth in my Patent No. 1,156,061.

Said mechanisms possess certain features in common with the mechanism shown and described in the present application which is subordinate to said Patent No. 1,455,109 and said application Serial No. 188,771. The special objects of the present invention are to provide power-actuated mechanism positively connected with a shift-frame to force the same into normal position as well as into upper-case position; to provide power-actuated shift-frame-moving means arranged to positively hold the shift-frame against vibration in both upper and lower-case positions; to provide yieldably compressible thrust-means for forcing the shift

frame to upper case position; to provide power means normally moving the shift-frame-moving mechanism to lower-case locked position and holding it there and power means for actuating the shift-frame-moving means to upper case position; to provide a latch operating always to lock the shift frame in upper case position which latch is releasable by operation of a temporary shift key as a release key after operation of a shift-and-lock-up key or is releasable upon release of the temporary shift key after a depression of said key made for effecting a change to upper case; to provide a power-driven case-shift mechanism embodying a friction clutch for connecting the case-shift mechanism with a source of power and means for automatically locking the case-shift mechanism in upper case position, wherein the clutch members are moved into engagement upon depression of a clutch-operating key and are automatically disengaged when the movement of the shift-frame to upper case position is completed and while the key is still held depressed, the release of the key serving to effect unlocking of the shift frame; and to provide a latch operating to lock the shift frame each time it is moved to upper case position, which latch is released during the down stroke of a combined shift and release control key if the shift-frame is in upper case position when said key is depressed and is released on the up-stroke of said key when said key is actuated to cause an upper-case shift movement of the shift frame. Other objects and advantages of the invention will appear from the following description of the mechanism illustrated in the drawings.

In the drawings—

Fig. 1 is a vertical longitudinal sectional view of a typewriting machine embodying my mechanism, the parts being shown in normal, lower case position;

Fig. 2 is a vertical sectional view in detail showing the tripping mechanism enlarged, the parts being in the same position as shown in Fig. 1;

Fig. 3 is a vertical sectional view of the lifting and tripping mechanism, the parts being shown locked in upper case position at the end of the down-stroke of the key of one of the temporary shift levers 53;

Fig. 4 is a view similar to Fig. 2 show-

ing the positions of the parts at the end of the down-stroke of the key of the lock-up shift lever 43;

Fig. 5 is a view similar to Fig. 3 showing the positions of the parts after release and return of the key of lock-up shift lever 43;

Fig. 6 is a section on the line VI—VI of Fig. 7;

Fig. 7 is a section on the line VII—VII of Fig. 8;

Fig. 8 is a detail plan view of the lifting mechanism as well as the clutch mechanism;

Fig. 9 is a detail perspective view showing the manner of lifting the tripping bail;

Fig. 10 is a detail perspective of the tripping and lifting mechanism;

Fig. 11 is a sectional view on the line XI—XI of Fig. 8;

Figs. 12 and 13 are enlarged views showing the lifting and tripping mechanism in different positions hereinafter described.

Referring to the drawings annexed, the numeral 15 designates a rod affixed to a swinging platen-carrying frame 16 mounted on the platen-carriage 17, this rod extending substantially across the machine. Connected to this rod 15 is a lifting-bar 18, the attachment being such that connection will be maintained with the rod 15 at all points in the travel of the carriage. For this connection, I prefer providing the rod 18 with a roller 19 which runs along the under side of the rod 15 and also with a hook 20 which extends over the top of the rod 15 so that the platen-frame will respond quickly to the motor-operated movements of the lifting-rod. This lifting-rod is guided vertically by a pair of pins 21 mounted in brackets on the frame of the machine, and desirably also it is provided with a shock-absorbing coil-spring 22, the lifting-rod being constructed of two sections adapted to have a limited sliding movement on each other to permit the spring to yield slightly in its upward thrusts to thereby relieve the mechanism of strain and jar and compensate for inaccuracies of fit of the parts.

The lower extremity of the lifting-rod is pivotally connected at 23 to the upper end of a short link 24, and the lower end of this short link 24 is connected to the outer end of an arm 25 affixed to a rock-shaft 26 journaled in suitable brackets 27 in the frame of the machine. A spring 28 is coiled around shaft 26 with one end secured to the inner bracket 27, as shown in Figs. 8 and 11, and has one free end in engagement with the front edge of another arm 29 affixed to the other end of shaft 26, the tendency of this spring being to rock said shaft and arm 29 over backwardly.

The end of the arm 29 is pivotally connected by means of a link 30 to a segment 31

pivottally mounted on the back wall of the frame of the machine and having its teeth in constant engagement with a pinion 32, said pinion being affixed to a friction-disk 33 loosely journaled on a counter-shaft 34 journaled in suitable bearings on the back wall of the machine and suitably belted so as to be run continuously from a motor 35. The friction-disk 33 is adapted to have a slip-friction engagement with a companion disk 36 slidably splined to said shaft 34, this engagement of the two disks being brought about by swinging inwardly the lower end of a lever 37 pivoted at 38 and having a roller-carrying arm 39 which extends upwardly so as to engage the off-side of the slidable disk 36. The lower end of the lever 37 is adapted to be swung inwardly to clutching position by any suitable means controlled from a key in the keyboard of the machine. I have shown this lever 37 as being provided with a laterally-extending bevel-nose 40 which is adapted to be engaged by the downwardly-swinging arm 41 of a transversely extending sub-lever pivotally mounted at the rear of the machine in such position as to adapt its opposite end 42 for upward movement through the medium of a shift-key-lever 43.

It will be observed that when the rear end of the shift-lever 43 is elevated, the inner end of the arm 41 will be swung downwardly and caused to impinge against the beveled edge of the nose 40 and thus swing the lower end of lever 37 inwardly. This will bring the clutch-disks into action, it being remembered that the counter-shaft 34 is kept in continuous revolution. Loose disk 33 will thus be carried around with the shaft 34, thereby causing the pinion 32 to rock the segment 31 downwardly. This will cause the link 30 to rock shaft 26 and thus increase the tension on coil-spring 28 and also cause the link 24 to lift the platen-frame through the medium of the lifting-rod 18. The platen-frame will be limited in its movement by suitable stops shown in Fig. 1 at 44, and the downward throw of the segment 31 will be positively limited in movement in a suitable manner, preferably by an adjustable stop-screw 45 affixed to the back wall of the machine. The return movement (hereinafter described) of the segment 31 will be limited by a similar stop 46. It will be observed that all the operator needs to do is to depress the key-lever 43 far enough to bring the clutch-disks into operation, whereupon the motor takes up the work of lifting the platen, but, should the operator maintain finger pressure on the key, the disks will readily slip one on the other, thereby avoiding any harm to the mechanism. In view of the fact that the work of lifting the platen-frame is very light, it will obviously need but a slight

touch of the finger on the key-lever 43, and, in order to hold the clutch-disks together under resilient tension, to thereby avoid a too-positive gripping action of the clutch-disks, I make the clutch-lever 37 transversely resilient so that its comparatively long depending arm will yield as soon as the clutches have come into contact.

When the platen is thus lifted to upper case position by direct actuation of key lever 43, it will be locked in that position (as shown in Fig. 4) by means of an automatic latch-lever 47 pivoted at 49 to one of the brackets 27 and having its depending end pulled rearwardly by means of a coil-spring 50, the upper laterally-bent end 51 of this latch lying in the path of the upwardly-moving link 24 so that rearwardly-extending lug 52 on the rear edge of said link 24 will snap over the bent end 51, thus preventing the return of the parts to normal after the key-lever 43 is released (as shown in Fig. 5). It will be understood that this lever 43 will be used when it is desired to lock the platen in upper case position. When it is simply desired to raise the platen temporarily for the writing of a single character or a few characters, either one of temporary shift key-levers 53 is employed and one or the other of these levers 53 is likewise employed when it is desired to release the latch 47 to permit the parts to return to lower case position. When said latch-lever 47 is thus released, the parts are quickly returned to normal by the previously-tensioned spring 28, the parts being arrested in proper position by the segment 31 coming into abutting relation with the upper screw-stop 46.

The rear end of each of the key-levers 53 is bent upwardly and then laterally to engage under one of the side arms of a bail 54 whose forwardly-extending side-arms 55 are pivoted at 56 to brackets 57 affixed to the side walls of the frame, the pivotal connections at 56 being loose so that the bail-bar 54 gravitatingly rests upon the upturned ends of key-levers 53. The bar 54 is provided with a forwardly-extending lug 58 which, when the bar is lifted through the medium of either key-lever 53 after a shift and lock-up operation effected by actuation of key lever 43, impinges against a bevel-lug 59 on the latch-lever and thus swings the latch-lever to non-latching position, thereby releasing the lug 52 and permitting the spring 28 to restore the lifting mechanism to normal. The release and return of the shift frame takes place on the down-stroke of the key of the active lever 53 when said lever is actuated solely as a release lever.

As stated above, either key-lever 53 is employed for the additional purpose of causing a movement of the platen to upper case position and holding the platen up merely as

long as the key of said lever is held depressed. For this purpose, I pivot to the key-lever 43 an upwardly-extending hook 60 which is normally pressed forwardly by a coil-spring 61 so that a shoulder 62 on said hook will normally engage over the top edge of the bail-bar 54, so that when said bail-bar 54 is raised through the medium of the temporary key-lever 53 this hook 60 will cause the companion key-lever 43 to be likewise elevated at its rear end, as shown in Fig. 12, thus putting into operation the clutch mechanism just as when the key-lever 43 alone is operated. When the lifting mechanism is thus put into operation by means of this temporary lever 53, it is desirable that the companion lever 43 shall be immediately released so as to immediately release the clutch and thus prevent grinding of the clutch members during the time the platen is held up by pressure on the key-end of the lever 53. This release of the lever 43 is accomplished by providing an automatic device for disconnecting the hook 60 from the bail-bar 54 to thus permit the lever 43 to gravitate to normal position. A simple way of doing this is to provide the arm 29 with a lateral finger 63 which, when the arm is rocked through the medium of the push-link 30, engages under an upwardly-and-forwardly-extending finger 64 formed by an extension of the hook 60 and thus forces this hook 60 backwardly (as shown in Fig. 13) against the action of its spring far enough to permit it to drop off the bail 100 and the parts assume the positions shown in Fig. 3. This release-finger 63 not only serves to disconnect the hook 60 in the manner just described, to permit the long key-lever 43 and the clutch mechanism to be released, but it serves the other purpose of camming the hook 60 rearwardly when the key-lever 43 is operated directly and holding it out of the path of the bail-bar 54 (as shown in Fig. 4), thereby permitting the key-lever 43 to 105 go back to normal without engaging the hook 60 with the bail-bar 54, (as shown in Fig. 5), and also leaving the bail free to be elevated by the companion key-lever 53 when it is desired to actuate the same for releasing the latch 47 in the manner hereinbefore described. It will thus be observed that, whether the lifting mechanism be put into operation directly through the key-lever 43 or the key-lever 53, the hook 60 will be actuated by the fingers 63 and 64 to release position as soon as the platen has reached its upper case position, so that in every case the key-lever 43 and the clutch member operated thereby will be free to return to normal, whether the platen is raised temporarily or to stay up.

We have seen that when the platen is raised by key-lever 43 alone to stay up, the latch 47 automatically locks it up and 115 120 125 130

that through the medium of the other key-lever 53 and the bail this latch-lever may be released to thus permit the mechanism to go back to normal through the action of coil-spring 28. Now, when the power-actuated shift mechanism is put into operation through the medium of the key-lever 53, the lug 58 will, of course, actuate the latch in the same manner as when the bail 54 is raised for release purpose only. This actuation of the latch will be an idle one, as the latch at that time is not in engagement with the lug 52; but, when the bail-lug 58 passes up beyond the cam-lug 59, the spring 50 will snap the locking-end 51 of the latch into position to be interlocked with the lug 52 when the platen-lifting action is completed. The parts remain in this position, namely in the position shown in Fig. 3, so long as the operator depresses the key on lever 53, but when lever 53 is released the bail-bar 54 gravitates with the lever 53 and thus causes lug 58 to impinge upon the upper bevel-face of the lug 59 and thus cause a release movement of the latch, whereupon, as formerly described, the spring 28 quickly restores the parts to normal and through hook 20 on rod 18 positively jerks the platen down, the clutch having, as above stated, been previously released and the hook 60 having been thrown back by finger 63 to release position. It will be observed that when the platen-frame is down the members 18, 24 and 25 will lie in vertical alinement, that is, with their centers of movement in the same vertical plane, so that the parts will be virtually on dead center and thus lock the platen against vertical vibrations through rod 18 and hook 20 during the printing operations. This dead-center position is nicely adjusted and maintained by the top stop-screw 46 against which the segment 31 is held by the action of the spring 28. It will be understood also that the spring 22 in the platen-shifting rod normally tends to expand and that the sudden pushing action on this rod 18 tends to further compress this spring, thereby not only dissipating the jarring action that would otherwise result from the very quick action of the motor-driven actuating mechanism, but also tending to hold the carriage against up-and-down vibrations during the writing operations.

55 The nature and scope of the invention having been thus indicated and its preferred embodiment having been specifically described, what is claimed as new is:

60 1. In a typewriting machine, a motor driving a continuously-rotated shaft, and a case-shifting mechanism actuated from said shaft, said mechanism embodying a push-and-pull rod connected to the member to be shifted, said rod being yieldingly con-65 tractible, for the purpose set forth.

2. In a typewriting machine, a power-driven case-shift mechanism and key-controlled devices for putting the same into action to shift said case-shift mechanism, said mechanism embodying a push-and-pull 70 rod, a rock-shaft and a link connecting the same to said rod, this link being provided with a catch, a latch adapted to automatically engage said catch when the mechanism is shifted, said key-controlled devices including means for disconnecting said latch to permit the case-shift mechanism to return to normal. 75

3. In a typewriting machine, a power-driven case-shift mechanism embodying a 80 rock-shaft and devices whereby it is rocked by power of the motor, a coil-spring surrounding this shaft adapted to be tensioned when the mechanism is shifted, an arm on said rock-shaft, a link connected to said 85 arm, a push-and-pull rod connecting said link to the shifting frame of the machine, means for latching the parts in their shifted position, and key-operated devices for releasing said latch. 90

4. In a typewriting machine, a power-driven case-shift mechanism embodying a continuously-rotated shaft, key-controlled devices for putting said mechanism into action to change case, said mechanism embodying a push-rod connected to the member to be shifted, said rod being constructed of two sections and a spring tending to press the sections apart, means being provided for permitting the spring to yield when the shifting mechanism is actuated in one direction and to limit the separating tendency of the spring. 95

5. In a typewriting machine, a case-shift support and means for positively arresting it in its shifted position, power-driven shifting mechanism under control of the key embodying a push-rod adapted to force said case-shift-support against its stop, said push-rod being yieldably compressible, and a key-controlled locking-device for holding said rod under compression while the case-shift-support is in its shifted position. 105 110

6. In a typewriting machine, a case-shift-support, power means for shifting said support from its normal case position to a different case position, an additional power means tending to normally move said support to its normal case position, a latch for automatically locking the support 115 in its shifted position against the action of said additional power means, and a key-controlled device operatively connected to actuate the first-mentioned power means when moved in one direction and to release 120 the latch when said key-controlled device is moved back to its normal position. 125

7. The combination with a typewriting machine, of case-shift mechanism comprising a shift-support, means for moving said 130

- support to vary the relation between the printing instrumentalities and the platen, a constantly-driven power-shaft normally disconnected from the support-moving means, a shiftable bar extending transversely of the machine, means operable by movement of said bar in one direction for temporarily connecting the power-shaft with the support-moving means, manually-operable means for moving said bar to operate the connecting means, means for automatically locking the support in its shifted position, said locking means being released by said bar during the return movement of the bar to release the support, and manually-operable means for operating the connecting means independently of said bar.
8. The combination with a typewriting machine, of case-shift mechanism comprising a shift-support, means for moving said support to vary the relation between the printing instrumentalities and the platen, a constantly-driven power-shaft normally disconnected from the support-moving means, a shiftable bar extending transversely of the machine, a pair of key-levers located at opposite sides of the machine and adapted to shift said bar independently of each other, means operable by movement of said bar in one direction by either of said levers for temporarily connecting the support-moving means with the power-shaft, means for automatically locking the support in its shifted position adapted to be operated by the return movement of the bar to release the support, and a third key-lever adapted to operate the connecting means independently of the shiftable bar.
9. In a typewriting machine, a case-shift-support, power mechanism for shifting said support, means being provided for locking the support to the shifting mechanism to prevent independent vertical movement of the support, automatic devices for locking the shifting mechanism in its shifted position, and key-controlled devices for putting the shifting mechanism into operation and for releasing said locking devices.
10. In a typewriting machine, the combination of a platen carriage, a shift-frame movable up and down, a platen mounted on the shift-frame, means for limiting the up-and-down movement of the shift-frame, a crank-shaft, a pitman operated by the crank-shaft and having a connection at its upper end with the shift-frame adapted to permit transverse movement of the shift-frame and prevent vertical movement thereof relatively to the pitman, key-controlled power-operated means for rotating the crank-shaft through a partial revolution from its normal position on a dead center at the lower limit of its throw to elevate the shift-frame, means for automatically lock-
- ing the parts so as to hold the platen in its elevated position, an independent key-controlled means for releasing the platen, and power means for rotating the crank-shaft in the reverse direction to lower the platen when the platen is released.
11. In a case shift mechanism, the combination of a shift frame, a constantly-operating shaft for actuating said shift frame, a key, means actuated by depression of said key for connecting said shaft to the shift frame to move the shift frame to upper case position, means independent of the key for automatically disconnecting the shaft from the shift frame, means independent of force applied to the key for holding the shift frame against return to lower case position while said key is manually held depressed, said holding means being releasable to free the shift frame during the up-stroke of said key when said key is released, and a spring tensioned by power from said shaft during movement of the shift frame to upper case position for restoring the shift frame to lower case position.
12. In a case-shift mechanism, a key, a shift frame, a constantly running motor for actuating the shift frame, a clutch for connecting the motor with the shift frame, clutch-shifting means operable by the key, and means operable by power from the motor for disconnecting the clutch-shifting means from the key upon movement of the shift frame by the motor into upper case position independently of the release of manual pressure on the key.
13. In a case-shift mechanism, a key, a shift frame, a constantly running motor for actuating the shift frame, a clutch for connecting the motor with the shift frame, clutch-shifting means operable by the key, means operable by power from the motor for disconnecting the clutch-shifting means from the key upon movement of the shift frame by the motor into upper case position independently of the release of manual pressure on the key, means independent of force applied to the key for holding the shift frame in upper case position, and means controlled by the key for freeing the shift frame from said holding means upon release of the key.
14. In a typewriting machine, a main frame, a shaft journaled on the main frame, a motor for driving said shaft continuously when the machine is in use, a friction clutch having its driving member fixed on said shaft and its driven member loose on said shaft, a shift frame, means connecting the loose clutch member with the shift frame for elevating the shift frame, a clutch shifter, a shift-and-lock-up key lever operatively connected with said shifter to effect engagement of the clutch

- members when its key is depressed and maintained such engagement until release of the key, a shift-and-release key lever, a movable element supported on the main frame and arranged to be elevated by the shift-and-release key lever upon depression of the key thereof and to be lowered upon release of the key, a hook member pivoted on the shift-and-lock-up key lever and normally spring-urged to engage over said movable element, means movable by said clutch and shift frame connecting means for rocking said hook out of cooperative relation with said element as the shift frame moves into upper case position and holding it out until a return movement of the shift frame takes place, and an automatically acting latch for locking the shift frame in upper case position, said latch and element having coacting cam portions for shifting the latch to release position during both upward and downward movements of said element.
15. In a typewriting machine, a power-shaft driven continuously while the machine is in use, a case-shift mechanism including a friction clutch for connecting the same with said shaft and means for limiting the throw of said shift mechanism, key-operated means for effecting engagement of the members of the clutch, means operable by the shift mechanism for freeing the clutch members from engagement upon movement of the shift mechanism a full throw by power from said shaft and while pressure is maintained on the clutch operating key, and means for automatically locking the shift mechanism in shifted position, said locking means being releasable by said key-operated means upon release of the key.
20. 16. In a typewriting machine, a power-shaft driven continuously while the machine is in use, a case-shift mechanism including a friction clutch for connecting the same with said shaft and means for limiting the throw of said shift mechanism, key-operated means for effecting engagement of the members of the clutch, means operable by the shift mechanism for freeing the clutch members from engagement upon movement of the shift mechanism a full throw by power from said shaft, and while pressure is maintained on the clutch operating key, means for automatically locking the shift mechanism in shifted position, said locking means being releasable by said key-operated means upon release of the key, and a spring connected with the shift mechanism and tensioned by movement thereof under power from the shaft for restoring the shift mechanism when said locking means is released.
25. 17. In a typewriting machine, a power- driven case-shift mechanism, a source of power, a first key lever, means operated by said first key lever for connecting said mechanism with the source of power, an automatic latch for locking the case-shift mechanism in upper case position, a second key lever, and means whereby the second key lever operates to release said latch on the down stroke of its key if the shift mechanism has already been moved to upper case position through an actuation of the first key lever, or, if the case-shift mechanism is in lower case position, operates to connect the shift mechanism with the source of power on the down-stroke of its key and to release said latch on the up-stroke of its key.
30. 18. In a typewriting machine, a case-shift mechanism, a source of power, a first key for connecting the shift mechanism with the source of power to shift the mechanism to upper case position, an automatic latch for locking the shift mechanism in upper case position, a second key for releasing the latch, means whereby the second key is normally connected with the first key for actuating the first key and is automatically disconnected therefrom upon direct actuation of the first key, and means whereby the first key is automatically disconnected from the second key upon a movement of the shift mechanism to upper case position initiated by actuation of the second key.
35. 19. In a typewriting machine, a case-shift mechanism, a shaft driven continuously when the machine is in use, a friction clutch for connecting said mechanism with said shaft to effect movement of the mechanism into upper case position, a first key lever for actuating said clutch, a latch arranged to automatically lock the shift mechanism in upper case position, a second key lever, connecting means effective only when the case shift mechanism is in lower case position whereby the second key lever may actuate the first key lever, means effective on said connecting means to automatically free said first key lever from the second key lever upon a movement of the shift mechanism into upper case position initiated by the second key lever and to prevent operation of the first key lever by the second key lever after an upper case shifting movement initiated by the first key lever, and means operable only by said second key lever for releasing said latch to permit restoration of the shift mechanism to lower case position.
40. This specification signed this fourth day of August, A. D. 1919.
45. MANSFIELD C. CRAWLEY
